UNITED STATES PATENT OFFICE

HENRY BOUSHEAR, OF FORT WILLIAM, ONTARIO, CANADA

PORTABLE TURNOUT

Application filed November 19, 1928. Serial No. 320,466.

My present invention has reference to a portable turnout for railroads and among my primary objects is the provision of a turnout designed for use upon mine tracks 5 and which is of such construction and arrangement that the same will rest upon and be rigidly fixed to the rails of the main track so that the device will not be overbalanced when loaded trains travel over one side of 10 the turnout and unloaded trains along the other side thereof; said turnout having rail extensions at the ends thereof which are tapered to provide a perfect incline for travel of the wheels of a mining car or train of cars on 15 or off the same; to provide a turnout which, by the operation of simple means, by unskilled laborers will bodily move the same longitudinally to desired positions on main track, as well as many other desirable features 20 of construction and arrangement of parts which will hereinafter be described and definitely claimed.

The invention will be fully and comprehensively understood from a consideration of 25 the following detailed description when read in connection with the accompanying drawings which form part of the application, with the understanding, however, that the improvement is capable of extended application and 30 is not confined to the exact showing of the drawings nor to the precise construction described and, therefore, such changes and modifications may be made therefrom as do not affect the spirit of the invention nor exceed 35 the scope thereof as expressed in the appended claim.

In the drawings:—

Figure 1 is a top plan view of approximately one-half of a turnout construction in 40 accordance with my invention.

Figure 2 is a side elevation thereof.

Figure 3 is a transverse sectional view on approximately the line 3—3 of Figure 1.

Figure 4 is a longitudinal sectional view 45 approximately on the line 4—4 of Figure 1.

Figure 5 is a transverse sectional view approximately on the line 5—5 of Figure 1.

Figure 6 is a sectional view approximately 50 on the line 6—6 of Figure 1.

Figure 7 is a detail enlarged sectional view on the line 7—7 of Figure 1.

Referring now to the drawings in detail, the numeral 1 designates the rails of a main track and 2 the ties on which the rails are 55 spiked. As both ends of my improvement are similarly constructed, I have thought the invention can be best illustrated by disclosing only one-half of the turnout. In this connection I desire it understood that the arrangement of the wheels of the turnout, that permit of the travel thereof over the main track to desired positions, is only arbitrarily shown by the drawings, as the said wheels 60 may be variously located throughout the length of the improvement and, of course, any desired number of pairs of wheels may be employed.

Resting on the main rails 1, at desired spaced intervals there are the shoe members 70 3 of the improvement. The shoe members, at the ends of the turnout are, of course, of shorter length than those upon which the double tracks of the turnout are positioned. The shoes may be of any desired comparatively cheap material, and have their upper faces grooved longitudinally throughout their lengths. In the groove of the shoes 3 there are received the depending side flanges 5 of 75 the transverse metal rail supporting plates or ties 4 of the improvement. Keys, preferably in the nature of headed pins 6, pass through the flanges 5 and through the shoes for effectively sustaining the ties or plates 4 80 on the shoes. By reference to the drawings it will be seen that the outer sides of the shoes have their top portions flush with the faces of the metal ties and that the top portions of their inner sides are in contact with the 85 inner faces of the ties. Thus the shoes not only support but brace and reinforce the ties and reduce the cost of maintenance as a worn or broken shoe may be cheaply and easily replaced.

The turnout includes two pairs of rails which are indicated for distinction by the numerals 7—7 and 8—8. The outer rails 7 and 8 adjacent their ends are curved inwardly, as at 7' and 8' respectively, and merge 95 100

into straight ends 9 and 10, and rest upon the end ties or plates 4 of the improvement. These straight ends 9 and 10, as disclosed by the drawings, are arranged in a line with the main rails 1 and rest on said main rails. Secured to the ends of the rail portions 9 and 10 of the tracks of the turnout there are rail extensions 11—11. The securing means between the rail extensions and the rail ends 9 and 10 are preferably in the nature of fish plates 12 which are integrally formed on the inner ends of the rail extensions 11, and which are received in the fishing spaces of the rail ends 9 and 10 and are bolted or otherwise secured thereto by means 13. By reference to Figure 2 of the drawings it will be seen that the rail extensions 11 have their upper faces gradually inclined or tapered, as at 14, so that the rail extensions merge into points. The bases 20 of the rail extensions rest directly upon the heads of the main rails 1. The tapered wheel elevating rail extensions 11 each, preferably, comprises an iron body or filler which is shod by steel and these members are held properly spaced by a spacer bar 15. The bar 15 is provided at its opposite ends with rightangled extensions 15^a which are secured by means of bolts 15^b to the rail extensions 11. These bolts pass through the rail extensions and have 30 swiveled or otherwise attached to their outer ends, forks 50. Secured to opposite ends of the bars 15 adjacent the rightangled extensions 15^a are chains 51 and these chains are brought under the main rails 1 and are hooked 35 in the forks and serve to lock the rail extensions 11 to the main rails 1.

The inner rails 7 and 8 of the respective tracks of the turnout are curved toward themselves over a metal tie 16, adjacent to the outer ties 4, the ends of the said curved portions contacting, jointed and merging into points. By reference to Figure 1 it will be noted that on the tie 16, outward of the rounded or curved ends of the rails 7 and 8, 40 there are guard rails 17, and extending from the guard rails there are curved switch rails 18 and 19, the said switch rails having their outer ends cut to correspond with the inner faces of the ends 9 and 10 of the outer rails 7 and 8. The switch rail 18 is influenced against the end 9 of the outer rail 7 by spring means, the latter comprising a bolt 20 that passes through the web of the switch rail 18 and through the web of the end 9 of the rail 7, the 45 said bolt having screwed on its outer end a nut 21 which compresses a spring 22 against the outer web of the rail end 9. A rod 23 is connected to the points of the switch rails 18 and 9 and is influenced by the spring 22 for holding the point 19 open. This arrangement is true with respect to both ends of the turnout. On the tie 16, inward of the curved portions 7' and 8' of the outer rails 7 and 8 of the turnout there are fixed curved guard rails 52 50 and 53, respectively.

As I have designated the widened and lengthened end ties by the numerals 16 I will also designate the inner ties by the numeral 24. All of the metal ties 4, 16 and 24, in the showing of the drawings are slotted longitudinally and transversely and the metal bounded by these slits are bent to provide clamps 25 which engage with the base flanges and webs of the rails of the turnout. The end of the ties may be bent, without being slotted to 75 provide the outer clamps.

The metal ties are provided with spaced pairs of openings 26 for chains 27 that are brought under the main rails 1 and have keys 28 passed through certain of their links to contact with the outer faces of the ties and thus lock the turnout on the main track. One end of the chain may, if desired, be hung from the ties.

In the showing of the drawings I have fixedly secured upon one side of the central metal tie of the turnout a pair of spaced upstanding lugs 30, and to these lugs there are pivoted arms 31. Each of the arms 31 has a depending outer end 32. Journaled through 90 suitable bearing openings in the oppositely disposed arms 31 there is the shaft 33 for the grooved or flanged wheels 34 of the improvement, the said wheels resting on the rails of the main track. Connecting the depending 95 ends 32 of the arms 31 there is a shaft 35, and loosely and centrally connected with this shaft there is a rod 36. The rod is directed toward one end of the turnout, and it will be obvious that a pull upon the rod will swing 100 the arms 31 so that the wheels 34, serving as fulcrums will cause the turnout to be raised and the turnout as a whole will be moved to desired positions along the main track. Of course, the securing means, comprising the 105 chains 51 and 27, are released before the turnout is so raised.

When the chains are attached the turnout is so balanced that a train of empty cars may travel over one of the tracks thereof and a 110 train of loaded cars may travel over the second track thereof without causing the tilting of the turnout.

A turnout constructed in accordance with my invention will reduce the tramping costs 115 to the lowest possible minimum. The device may be kept the same distance from the working face of mines at all times by moving it forward after the several rounds of holes have been fired. The turnout permits the driller 120 to get back to the working face at the earliest possible moment as the muckers are enabled to muck much quicker because of the comparatively short tramping distance. The turnout eliminates the troublesome and costly 125 system of pulling up switches and crossings and moving the same so as to reduce the tramping distance and it also eliminates the employment of skilled trackmen as with the improvement they will not be required to lay 130

switches and crossings. The turnout can be readily moved either forwardly or backwardly in a comparatively short length of time by the employment of only two hands, as the 5 rod 36 may be connected with a pivotally supported lever, one hand being required to operate the lever and this hand and the other may now employ bars for moving the turnout bodily on its wheels. The upkeep of the improvement is practically negligible and it increases 10 the tonnage from the working face of the mine.

Having described the invention, I claim:—

The combination of a main track and a 15 turnout resting thereon, said turnout including rails comprising spaced tracks, switch members between the inner and outer rails at the ends of the turnout, tapered rail extensions fixed to the rails of the turnout resting 20 on the main track and removably secured thereto, transverse ties supporting the rails of the turnout, rail engaging means carried by said ties for holding the rails thereon, each of said ties having flanged sides, a grooved 25 shoe for each of said sides, keys securing the shoe to the flanges, means for removably fixing the turnout on the main track for balancing said turnout, swingable wheels carried by the turnout movable to engage with the 30 main track, and rod operated means for swinging said wheels to bodily elevate the turnout to permit of the longitudinal movement thereof on the main track, after the securing means for the turnout is released.

35 In testimony whereof I affix my signature.
HENRY BOUSHAR.
